(57) **CLAIM**

I claim the ornamental design for a 5GNR antenna, as shown and described.

DESCRIPTION

FIG. 1 shows a perspective view of a 5GNR antenna; FIG. 2 shows a front plan view of the 5GNR antenna; FIG. 3 shows a rear plan view of the 5GNR antenna; FIG. 4 shows a right plan view of the 5GNR antenna; FIG. 5 shows a left plan view of the 5GNR antenna; FIG. 6 shows a top plan view of the 5GNR antenna; and, FIG. 7 shows a bottom plan view of the 5GNR antenna. That which is represented by broken lines illustrates environmental subject matter only and does not form part of the claimed invention.
